COMPRESSOR

George F. Pfeifer, Quincy, Ill.

Application June 19, 1951, Serial No. 232,381

3 Claims. (Cl. 230—206)

1

This invention relates to a compressor for air or other gaseous medium, and more particularly to a lubricating system for such a compressor.

The object of the invention is to provide a lubricating system for a compressor which will insure that the compressor operates quietly, efficiently, and wherein hydraulic hammer will be eliminated.

Another object of the invention is to provide a compressor lubricating system which is constructed so that the compressor will operate without noise, the system of the present invention utilizing a plunger pump which draws in a small amount of air with the oil being pumped, the air acting as a cushion to thereby eliminate hydraulic hammer within the pump cylinder.

Still another object of the invention is to provide a compressor lubricating system which includes a spring loaded, adjustable by-pass mechanism for regulating the oil pressure as the oil leaves the pump, the lubricating system of the present invention including a pressure gauge which is of simple and rugged construction and wherein the gauge is provided with stop mechanism for preventing damage to the gauge in the event the oil pressure exceeds a predetermined degree.

A further object of the invention is to provide a lubricating system for the compressor which is extremely simple and inexpensive to manufacture.

Other objects and advantages will be apparent during the course of the following description.

In the accompanying drawings forming a part of this application, and in which like numerals are used to designate like parts throughout the same:

Figure 1 is a fragmentary end elevational view of a compressor provided with the lubrication system of the present invention;

Figure 2 is a sectional view taken on the line 2—2 of Figure 1;

Figure 3 is a sectional view taken on the line 3—3 of Figure 2;

Figure 4 is a sectional view taken on the line 4—4 of Figure 2;

Figure 5 is an enlarged sectional view taken on the line 5—5 of Figure 1;

Figure 6 is a sectional view taken on the line 6—6 of Figure 1;

Figure 7 is a sectional view taken on the line 7—7 of Figure 1;

Figure 8 is an enlarged front elevational view of the pressure gauge;

2

Figure 9 is an enlarged fragmentary sectional view taken through the plunger and valve assembly;

Figure 10 is a sectional view taken on the line 10—10 of Figure 9;

Figure 11 is a sectional view taken on the line 11—11 of Figure 9.

Figure 12 is a sectional view taken on the line 12—12 of Figure 2.

Referring in detail to the drawings, the numeral 10 designates a crank case which forms part of a compressor, and the crank case 10 includes a bottom wall 11 and vertically disposed end walls 12 and 14, Figures 1 and 2. The case 10 further includes vertically disposed, spaced side walls 15, and a horizontally disposed top wall 16. Mounted in the end wall 12 is a bearing race 17, and a plate 18 is detachably connected to the end wall 14 by suitable screws or bolts 19. The plate 18 provides a support for a bearing race 20, Figure 2.

The present invention is directed to a lubrication system for a compressor, such as a compressor used in compressing air, and the lubrication system includes a crankshaft which is indicated generally by the numeral 21. The crankshaft 21 includes a pair of cylindrical end portions 22 and 23, the end portion 22 being rotatably supported in the bearing race 20, while the end portion 23 is rotatably supported in the bearing race 17. The crankshaft is further provided with a pair of webs 24 and 25 which are spaced from each other, and arranged between the webs 24 and 25 is a pair of crank pins or eccentric sections 26 and 27, the sections 26 and 27 being arranged off center with respect to the longitudinal axis of the crankshaft 21. A bearing 28 is arranged in engagement with each of the eccentric sections 26 and 27, and the lower ends of the usual connecting rods 29 engage the bearing 28. The upper ends of the connecting rods 29 are connected to the usual pistons for compressing air during the reciprocation thereof.

Arranged between the pair of eccentric sections 26 and 27 and formed integrally with the crankshaft 21 is an offset portion 30, Figure 3. Rotatably embracing or engaging the offset portion 30 is a strap 31, the strap 31 including a pair of sections 32 that are detachably connected together by a bolt 33. Strap 31 is provided with a socket 34 which receives therein the head 35 of a movable plunger 36. A bolt or screw 37 serves to maintain the plunger 36 connected to the strap 31. Thus, upon rotation of the crankshaft 21, the plunger 36 will be caused to reciprocate. This is due to the fact that the center of

the offset portion 30 is offset from the center of the crankshaft, as best seen in Figure 3.

Extending into the case 10 is a fulcrumed bearing shaft or pin 38, Figure 2. The pin 38 includes an exteriorly threaded portion 39 that is arranged in threaded engagement with the end wall 14 of the case 10, and the pin 38 is further provided with a head 40 which is adapted to be engaged by a suitable tool, such as a wrench, for removing or replacing the pin 38. The pin 38 is provided with a bore 41 that extends longitudinally therethrough for a portion of its length, and a plurality of radially extending ports 42 communicate with the bore 41, there being a gasket 43 interposed between the head 40 and the adjacent portion of the crankcase. The pin 38 is further provided with an annular groove 44 that communicates with the ports 42. The pin 38 is further provided with a second set of ports 45 which communicate with the bore 41, and an annular groove 46 communicates with the outer ends of the ports 45. An opening 47 extends through a portion of the pump body 49, the opening 47 connecting the groove 46 to a passageway 48 which is arranged in the pump body.

The body 49 is further provided with a shoulder 50, and mounted on the shoulder 50 is a screen 51 which serves as a filter element, so that oil which is being pumped from the case 10 will be filtered. The oil that is being pumped enters the body 49 through a passageway 52, and communicating with passageway 52 is a bore 53 and vent 54, the vent 54 being arranged in engagement with the bore 52 in the body 49, Figures 2 and 9, the vent being provided for the ingress therethrough of air. As later described in this application, during reciprocation of the plunger 36, a small amount of air will be drawn into the pump body through the opening or vent 54, whereby the air will become intermixed with oil passing through the lubricating system, so that the air will act as a cushion and help eliminate noise.

The plunger 36 is hollow or is provided with a chamber 55, Figures 9, 10, and 11, and a plurality of ports 56 communicate with the chamber 55, the ports 56 terminating in an annular groove 57 that is arranged in the plunger 36. A portion of the annular groove 57 is at all times in communication with the passageway 48. When the plunger 36 is moving to its downward position oil will be forced from the chamber 55' through the port 61, then through ports 56, through the groove 57 and into the passageway 48. Arranged in the lower end of the plunger 36 is a valve assembly which includes a first valve 58 that is provided with a plurality of cut away portions 59. Valve 58 is mounted for movement into and out of bridging relation with respect to a valve seat 60, and the valve seat 60 is provided with a central opening 61 for the ingress therethrough of lubricating oil. Disposed below plunger 36 in the body 49 is a second valve seat 62 which is provided with a plurality of spaced, radially extending bores 63, the outer ends of the bores 63 communicating with an annular groove 64 that is arranged in the exterior of the valve seat 62. The inner ends of the bores 63 communicate with a chamber 65, and mounted for movement into and out of closing relation with respect to the upper end of the chamber 65 is a valve 66, the valve 66 having the same construction as the previously-described valve 58. The valve 66 is shown in detail in Figure 10, and

the valve 66 is provided with a plurality of cut-outs or cut away portions 67, so that when the valve 66 is in its raised position during the up stroke of the plunger 36, oil will flow from the chamber 65 past the cutout 67 and then into the oil chamber 55', due to the creation of a vacuum. A washer 68 is arranged contiguous to the upper surface of the valve seat 62 for maintaining the valve 66 in its proper spaced position.

Arranged in the plate or bearing carrier 18 is a chamber 69, Figure 2, and the chamber 69 has a bore 70 communicating therewith for conveying oil thereto. The bore 70 communicates with a bore 71 which is arranged in the end wall 14, and the bore 71 communicates with the annular groove 44. Thus, lubricating oil will pass from the pin 38 through the bores into the chamber 69. This lubricating oil will then pass through a passageway 72 which is arranged in the crankshaft 21, and from the passageway 72 the lubricating oil is forced through a passageway 73 into a passageway or bore 74 which is arranged in the crankshaft 21. A portion of the lubricating oil will pass from the passageway 74 through channelways 75 and 76, whereby the oil will conveniently lubricate the lower parts of the connecting rods.

A spring loaded, adjustable bypass is provided for regulating the oil pressure in the system after the oil leaves the pump. Thus, all oil which is in excess of the required amount will be returned to the case sump. This by-pass mechanism is shown in detail in Figure 7, and comprises an adjusting screw 77 which is arranged in threaded engagement with the bearing carrier 18. The adjusting screw 77 is provided with a chamber 78, and the stem 79 of a valve 80 is slidably arranged in the chamber 78. The adjusting screw 77 projects into a compartment 81 which is formed in the bearing carrier 18, and the compartment 81 is connected to the chamber 69 by means of an opening or port 82. An inclined port 83 leads from the compartment 81 to the interior of the case 10. Carried by the adjusting screw 77 is a packing ring 84 which serves to prevent oil leakage, and a spring 86 normally urges the valve 80 into bridging relation with respect to the opening 82, there being a nut 85 for locking the adjusting screw 77 in place. Thus, in the event the oil pressure exceeds a predetermined value, the valve 80 will be moved downwardly, so that oil can flow from the chamber 69 through the port 82, then through the port 83 back into the sump. The tension on the valve 80 can be adjusted by rotating or varying the position of the adjusting screw 77.

The assembly of the present invention further includes an oil pressure gauge which is simple and fool-proof, and this gauge is shown in detail in Figures 5, 6 and 8. Thus, arranged in the bearing carrier 18 is a bore 87 which receives oil from a bore 71. This oil then flows from the bore 87 into a passageway 88, and thence the oil flows through a felt dampening member 89, so that pulsation in the flowing oil will be substantially reduced or eliminated before the oil acts on the gauge plunger. The felt dampening pad 89 is retained in its proper place by means of a screw plug 90, Figure 6. The lubricating oil then flows into a compartment 91 to urge the plunger or piston 92 upwardly against the tension of a coil spring 93. The coil spring 93 has the proper tension to correspond with the oil pressure and gauge reading. The upper end of the plunger 92 is arranged in engagement with a screw plug 94,

and the plunger 92 is provided with an annular groove 95. A port 96 communicates with the groove 95, whereby any oil that enters the annular groove 95 will be drawn back into the case

10. The crankcase is provided with a breather valve 98 which may be made of flexible material, and a stop member 97 serves to limit upward flexing movement of the valve 98. The members 97 and 98 are maintained in their proper position by means of a screw or bolt 99. The breather valve 98 thus causes the pressure inside the crankcase to be slightly lower than atmospheric pressure, since the movement of the compressor pistons cause the breather valve 98 to open and close. Therefore, as previously stated, any oil which enters the groove 95 in the plunger 92 will be drawn back into the case rather than escape past the plunger 92.

The gauge further includes a dial 100, the dial 100 being provided with suitable numerical graduations for indicating the oil pressure, as shown in Figures 1 and 8. A pointer arm 101 is arranged to move relative to the dial 100, and the pointer arm 101 is provided with, or has secured thereto, an extension pin 102 which projects into a groove 103 that is arranged in the plunger 92, Figure 6. Thus, as the plunger 92 moves up and down, the pointer arm 101 will be caused to move. The spring 93 is tensioned so that the movement of the plunger 92 will give a proper reading on the dial 100. The dial 100 is further provided with a lug 104, Figure 5, and the lug 104 is seated in a groove which is arranged in dial cover 105. A glass disc 106 is arranged between the dial 100 and the cover 105, and the dial, groove and cover assembly is fastened or secured to the bearing carrier by a plurality of suitable securing elements, such as screws 107.

A stop means is provided for preventing damage to the gauge in the event the pressure in the system exceeds a predetermined amount. This stop means comprises an annular flange 108 which is formed integrally with or secured to the plunger 92, and the annular flange 108 will abut a portion of the bearing carrier 18 to limit downward movement of the plunger 92. For limiting upward movement of the plunger 92, the screw plug 94 will be contacted by the upper end of the plunger 92. A passageway 112 extends from the passageway 14, whereby some of the lubricating oil can be used for lubricating the parts of the pump adjacent to the offset portion 30, Figure 3. A drain plug 109 is detachably connected to the crankcase, whereby the oil can be drained from the crankcase when desired.

The operation of the lubricating system of the present invention is as follows: The crankshaft 21 is rotated by any suitable means, and this imparts a reciprocating motion to the plunger 36. Then, on the up stroke the oil will flow from the sump or case through the screen 51, then through the bore 52, and into the body 49. This lubricating oil will then enter the annular space 64 which is formed by the valve seat 62, and this will then flow through the ports 63 in the seat 62 and enter the pump cylinder by passing through the cutout portions 67 in the valve 66. The valve 66 is raised slightly during the up stroke of the plunger due to vacuum. The diameter of the plunger 36 and stroke of the offset portion 30 are so proportioned that the oil cannot flow fast enough through the bore 52 to fill the cylinder 55' to full capacity. This means that the pump is trying to fill, but is re-

strained, so that air will be drawn through the bore 53, then through the bore 54, and this air will become intermingled or intermixed with the lubricating oil.

5 On the downward stroke of the plunger 36, the entrapped air in the pump cylinder acts as a resilient force at the beginning of the stroke, thereby eliminating the hydraulic hammer that is usually associated with high speed plunger pumps. The oil and air which are intermixed then flow through the openings 61 in the valve seat 60, and this oil flows around the wing guides or through the cutout portions 59 in the valve 58. This oil and air flows into the space 55 and then through the ports 56 into the annular space 57. The oil and air then flow through the bore 48, and then through the opening 47 into the fulcrum shaft 38. Then, the lubricating oil flows through the bores 71 and 70 and into the chamber 69 which is arranged in the bearing carrier 18. This lubricating oil then goes through the distributing ducts or passageways into the crank shaft 21 and then to the connecting rod bearings. The spray from the crank pins and connecting rods provides lubrication for the upper ends of the rods and cylinders.

20 The chamber 110 is normally filled with air at atmospheric pressure, but as soon as the pump delivers oil, the entrapped air in the chamber 30 110 will be alternately compressed and expanded to thereby eliminate most of the pulsations in the oil line. The pressure setting at which the system is set to operate is controlled by the bypass valve 80 which is slidably mounted in the 25 adjusting screw 77. The screw 77 is locked in place by the nut 85, and the screw 77 is provided with the packing ring 84, Figure 7, for preventing oil leakage. The oil pump body 49 is provided with a vent 111, Figure 2, and the vent 111 prevents the oil that escapes past the end of the fulcrum shaft 38 from building up pressure and thereby moving the pump laterally. The duct 87 in the bearing carrier 18 is arranged in alignment with the ports 71 in the case 10, and lubricating oil is fed through the dampening felt pad 89 to the under side of the gauge plunger 92, thus forcing the gauge plunger 92 upward against the tension of the spring 93. The plunger 92 is provided with the annular space 95 which aligns with the vent hole 96 in the carrier 18.

35 Dial 100 on the indicating gauge is provided with numerical graduations for indicating the oil pressure, and the pointer arm 101 is mounted for movement relative to the dial 100. The pointer arm 101 has secured thereto the extension pin 102 which projects into the groove 103 in the plunger 92. Thus, as the plunger 92 moves up or down, this movement will be transmitted to the pointer arm 101. The spring 93 is tensioned so that the movement of the plunger 92 gives the proper gauge reading. The screw plug 94 serves to limit up travel of the plunger 92, so that damage to the gauge will be prevented in the event the oil pressure exceeds the setting of the bypass valve.

40 Further, the movements of the compressor system cause the breather valve 98 to alternately open and close with respect to the breather opening therebelow. Thus, the pressure inside the case 10 will be slightly lower than atmospheric pressure, and this reduced pressure in the case causes any oil that works past the plunger 92 into the groove 95 to flow through the ports 96 back into the case. Also, the intake valve 66 and the exhaust valve 58 are of identical construction,

so that the lift can be held to a minimum and therefore these valves will be quiet in operation.

From the foregoing it is apparent that a lubricating system for a compressor has been provided whereby the oil is supplied under pressure by a plunger-type oil pump which includes both inlet and exhaust valves. The construction of the pump is such that it is quiet running and entirely free from hydraulic hammer. The plunger-type oil pump will function efficiently even though the compressors are operated in alternate directions and further, the hydraulic hammer will be eliminated even though the pump may be operating at a high speed, or even though the compressors may be operating at a high rate. Thus, ordinarily, a definite hydraulic hammer is set up in the conventional pump momentarily when the plunger changes from the inlet to the exhaust motion, due to the fact that the oil is at rest momentarily at the end of the inlet stroke and must be started in an opposite flow. Thus, at this time the oil is in a more or less solid condition when the hydraulic hammer occurs. The system of the present invention overcomes this hammer and eliminates the noise set up by uncovering an inlet port at the end of the inlet stroke, since the pump of the present invention is equipped with an inlet valve as well as an exhaust valve, and also, the stroke of the plunger is sufficiently great so that the piston displacement of the pump is greater than that required for the amount of oil needed, and further, the inlet passages are restricted so that at no time will the pump cylinder be entirely filled with oil. Thus, the bore 53 permits air to enter the vent 54 which is connected to the inlet passageway 52 so that a small amount of air will be taken in with the oil at each stroke, and this air then adds to the cushion when the plunger changes from inlet to exhaust stroke, to thereby eliminate all hydraulic hammer set up within the pump cylinder. Further, the spring loaded, adjustable by-pass is provided for regulating the oil pressure after leaving the pump. All oil in excess of the required amount is returned to the case sump.

Also, the built-in oil pressure gauge is simple and foolproof, and the oil is delivered to the under side of the spring loaded plunger 92 which has stops at both ends of its movement. Movement of the plunger in either direction causes the pointer arm 101 to move in an arc, and spring 93 has the proper tension to correspond with the oil pressure and the gauge reading. Further, the bearing carrier 18 is provided with an air cushion chamber 110 which also acts as an accumulator for some of the air in the oil, and this also is alternately compressed and expanded with each discharge of the pump plunger to thereby reduce the pulsation in the oil line. To further reduce pulsations of the oil acting on the gauge plunger 92, the length of felt 89 is used which can be compressed slightly during assembly to thereby further dampen out pulsations on the plunger 92 and other parts of the oil gauge. The seat 60 can be held in place on the bottom of the plunger 36 by rolling or swedging the edge of the plunger 36, and the valve and seat therebelow can also

be held in place by rolling or swedging portions of the pump body 49.

What is claimed is:

1. In an air compressor, a case provided with a bottom wall, spaced parallel side walls, spaced parallel end walls and a top wall, a bearing race mounted in one of said end walls, a bearing carrier detachably connected to the other end wall and arranged in opposed relation with respect to said bearing race, a bearing race mounted in said bearing carrier, a crankshaft having its ends rotatably supported by said pair of bearing races, a pair of eccentric sections arranged on said crankshaft, connecting rods having their lower ends pivotally connected to said eccentric sections, an intermediate offset portion arranged between said pair of eccentric sections, the center of said offset portion being offset with respect to the center of the crankshaft, there being interconnected passageways extending through said crankshaft for the passage therethrough of oil, a strap pivotally mounted on said offset portion and including a pair of sections detachably connected together, a plunger having one end connected to said strap, a fulcrumed bearing pin extending into said case and provided with a tool engaging head, said pin being provided with a longitudinally extending bore, there being a plurality of radially extending ports communicating with said bore, there being an annular groove communicating with said ports, a pump body mounted on the inner end of said pin and provided with a cylinder for slidably receiving said plunger, said pump body having a passageway connected to said groove, conduit means in said body, pin and bearing carrier for conveying oil to the passageways in said crankshaft, a vent in said body for intermixing air with the oil flowing through the system, a plurality of valves arranged in the lower end of said plunger for regulating the flow of oil through the pump body, a reticulated element mounted on said body for filtering the oil flowing into the body, and a spring loaded adjustable bypass valve including an adjusting screw arranged in engagement with said bearing carrier for regulating the oil pressure in the system after the oil leaves the pump.
2. The apparatus as described in claim 1, and further including a vent arranged in said pump body for preventing oil that escapes past the end of the fulcrumed pin from building up pressure and moving the pump laterally.
3. The apparatus as described in claim 1, and further including a gauge mounted in an end of said case for indicating the oil pressure in the system, stop means for preventing damage to the gauge in the event pressure in the system exceeds a predetermined amount, the pressure inside the case being slightly lower than atmospheric pressure, and a dampening member for reducing pulsations in the flowing oil.
